UNITED STATES PATENT OFFICE.

CHARLES P. NUTTER, OF MALDEN, AND JOHN E. CHATMAN, OF SWAMPSCOTT,
MASSACHUSETTS.

COMBINED HEATING AND SPRINKLER SYSTEM.

1,087,136.

Specification of Letters Patent. Patented Feb. 17, 1914.

Application filed May 26, 1906. Serial No. 318,814.

To all whom it may concern:

Be it known that we, CHARLES P. NUTTER, a citizen of the United States, and resident of Malden, county of Middlesex, State of Massachusetts, and JOHN E. CHATMAN, a citizen of the United States, and resident of Swampscott, county of Essex, State of Massachusetts, have invented an Improvement in Combined Heating and Sprinkler Systems, of which the following description, in connection with the accompanying drawing, is a specification, like characters on the drawings representing like parts.

Our invention has for its object to provide a novel sprinkler system which is capable of being used as a heating system so that by the installation of one circulating system a building can be heated and can also be provided with an automatic sprinkler system capable of extinguishing fires.

We attain the above object by so arranging the sprinkler pipes of the sprinkler system that a heating medium can be circulated therethrough, thus converting the said pipes into heating pipes.

Our invention, therefore, is a combined sprinkler system and heating system, or a single system capable of performing the functions of both a sprinkler system and a heating system.

During warm weather, when it is unnecessary to use the heating feature of the invention, the circulation of the medium in the pipes is stopped, but the pipes are always full of said medium and are ready for the extinguishing of fires whenever any of the sprinkler heads give way.

Other features of our invention will be more fully hereinafter described and then pointed out in the appended claims.

In the drawings we have illustrated largely diagrammatically one way in which our invention may be carried out.

Figure 1 is a vertical section through a building showing our combined sprinkler and heating system applied thereto; Fig. 2 is a horizontal section on the line x-x, Fig. 1; Fig. 3 is a detail of a sprinkler head.

In Fig. 1 3 designates the floors of a building which is equipped with our combined sprinkler and heating system, said building being herein shown as having five stories. The sprinkler pipes which extend throughout the building are designated by

8 and these are preferably placed near the ceiling or in such other places as will permit them to properly perform their sprinkling function when occasion arises. Each pipe has mounted thereon a plurality of automatic sprinkler heads 11 which may have any suitable or usual construction. The sprinkler heads herein shown are of a well-known type, and each comprises a valve 12 which closes a port 13 communicating with the sprinkler pipe 8 and which valve is held in place by a fusible retainer or connection 130 so that whenever sufficient heat is developed near the sprinkler head to melt the fusible retainer, the valve 12 thereon will open, thus allowing the contents of the pipe 8 to be discharged. In the arrangement as shown in the drawings, the pipes 8 are all connected at one end to a supply pipe 6 and are connected at the other end to a common return 7. In order that the pipes 8 may also be used for heating pipes, we propose to connect the supply pipe 6 with a heater 4 (this being done herein by means of the pipe or connection 5), and to also connect the return pipe 7 with the heater in some suitable way so that the medium which is circulated through the pipes 8 may be returned to the heater. It is within our invention to use any suitable medium in the pipes 8 which is both capable of extinguishing fires and of conveying heat to the pipes. We prefer, however, to use water, for water can be readily heated, circulated through the pipes 8 and returned to the heater again, and it also makes a most effective medium for extinguishing fires. If found necessary to keep up a proper circulation of the hot water through the pipes 8, a circulating pump 10 may be employed, although this will not be necessary under all circumstances.

In Fig. 1 the sprinkler pipes 8 are shown as connected directly to the supply pipe 6 and return pipe 7. In Fig. 2, said sprinkler pipes are connected directly to branches 9 which in turn connect to the supply pipe 6 and the return pipe 7. Provision is made, as will be more fully hereinafter described, so that the sprinkler pipes 8 are always maintained full of water and are therefore always ready to act as sprinkler pipes. Whenever the pipes are to be used also as heating pipes, the water in them is heated

and caused to be circulated therethrough. It is not necessary, however, to use the pipes as heating pipes except in cold weather, and in order that the heating function may be 5 eliminated without interfering in any way with the sprinkling function, we provide for stopping the circulation of the water through the pipes 8 whenever it is desired to shut off the heat. This can be conveniently done by arranging in each of the 10 pipes a valve 15 which when closed cuts off communication between said pipe and the return. When the valves 15 are opened and the heater 4 is in operation, a heating medium will be circulated through the sprinkler pipes, thus converting said pipes into 15 heating pipes. When the valves 15 are closed, the circulation of the heating medium is stopped and the heating function is 20 eliminated from the system without, however, disturbing in any way the sprinkling function thereof. We prefer to place a valve 15 in each of the pipes 8 so that any one of the pipes can be used separately for 25 heating purposes. The manner of connecting this combined system to the water supply so as to always maintain the pipes 8 full of water, whether the water is circulating therethrough or not, will vary according to 30 the circumstances of the case.

In Fig. 1 we have shown one simple layout which accomplishes the purpose without, however, limiting ourselves to this construction. In said figure, the circulating 35 pump 10, if one is used, is connected with the water main 21 by means of a suitable pipe 22 which will preferably have a valve therein. The water main is also shown as being connected to the supply pipe 6 40 through a pipe 23 which has a valve 30 therein. The supply pipe 6 extends to a pressure tank 24, said pipe being connected to the tank both by means of a connection 25 which leads into the bottom of the tank 45 and by a connection 26 which leads into the top of the tank. The connection 26 is provided with a float valve 27 adapted to close when the water in the pressure tank falls below a predetermined level. 29 is a check 50 valve situated in the pipe 25 and arranged to permit the water to flow from the tank 24 to the supply pipe 6 but not in the reverse direction, and 28 is a check valve arranged to permit the water to flow from 55 the pipe 6 through the pipe 26 to the tank, but not in the reverse direction.

The construction thus far described provides for a head of water in the tank 24 sufficient to keep the pipes 8 always filled 60 and said tank also allows for expansion of the water in the pipes when it is heated. There is sufficient water in the tank 24 to extinguish a small fire without drawing on the city supply.

65 As stated above, the valve 27 is so ar-

ranged as to close when the water level in the tank 24 drops below a certain point, so that after a certain amount of the water in the tank 24 has been drawn off for extinguishing a fire, or other purpose, said valve 70 will close. If the fire is of considerable dimensions, however, so that more water is needed for extinguishing it than is contained in the tank 24, the valve 30 in the pipe 23 may be opened and the risers or supply pipe 6 thus connected directly with the city main, in which case the pipes 8 will receive the full pressure of the city water. When the supply pipe 6 is thus connected to the main 21 the check valve 29 will prevent the water from flowing into the tank 24 through the connection 25, and the float valve 27 will prevent the water from flowing into the tank through the connection 26. All the water delivered from the city main 21 therefore is directed into the pipes 8 for 80 extinguishing the fire.

In many buildings a fire pump is stationed which may be put into play to pump the water under increased pressure to various parts of the building. In the drawings we have shown such a fire pump at 90 31, and it is illustrated as being connected to the source of water supply by a suitable pipe 33 and also connected to the pipe 26 by a suitable pipe 34, which is herein shown as having a stop valve 35 and a check valve 36 therein. Said fire pump may also be connected with the pipe 21 by pipes 37 and 38. With this arrangement by properly manipulating the valves 40, 41 and 42 the fire pump may be connected either with the return 7 or with the supply pipe 6 or with both and may be used to force water under any desired pressure through 95 the sprinkler heads.

In practice the fire pump or other means for getting increased pressure will not be started until after the water in the tank 24 has been drawn out sufficiently to permit the valve 27 to close. As a result, the increased pressure in the main 6 due to the fire pump or other pumping apparatus will not force the water into the tank 24, but will instead increase the pressure at the sprinkler 100 heads.

50 designates a supply pump which may be used if necessary for pumping water into the supply tank 24 through the pipes 34 and 26, it being understood that the float valve 27 will have to be raised by hand in order to open it to permit the water to be pumped into the tank 24. This particular arrangement of fire pump, supply pump and the special system of piping for supplying water to the system in case a sprinkler-head gives way, may be varied according to the circumstances of the case.

To prevent any possibility of any sprinkler head becoming opened by the heat con- 125

veyed to it by the heating pipe 8, we may if desired employ some suitable form of heat-insulated sprinkler head. Under ordinary circumstances, however, the heat generated in any pipe 8 will not be sufficient to melt the fusible connection of the sprinkler head. One simple way of heat insulating the sprinkler heads from the pipes 8 is illustrated in Fig. 3 wherein each sprinkler head 10 is shown as being screwed into a nipple 16 which in turn is screwed into a bushing 17 of suitable heat-insulating material that is carried by the T 18. The bushing 17 prevents the heat in the pipe 8 from being conveyed to the sprinkler head through the nipple 16, and the nipple 16 forms within it an air chamber, the air in which prevents the hot water from coming directly in contact with the valve. Any other suitable manner of insulating the sprinkler heads from the pipe 8 could be adopted, however, without departing from our invention.

It is apparent that the valves 15 may be adjusted to vary the flow of water through the individual sprinkler pipes without shutting it off completely, if desired, and if there should be any tendency of the water to flow through certain pipes rather than others, such tendency can be counteracted and "short-circuiting" of the water prevented 30 and a uniform distribution of the circulating water obtained by such adjustment.

The principal feature of our invention resides in arranging a sprinkler system so that the sprinkler pipes may be used for heating purposes, and we desire to claim this broadly.

Having fully described our invention, what we claim as new and desire to secure 40 by Letters Patent is:—

1. In a combined sprinkler and heating system, the combination with a plurality of sprinkler pipes and a plurality of sprinkler heads mounted on each pipe, of a supply pipe connected to all of said sprinkler pipes, a return also connected to all of said pipes, whereby said pipes form part of a complete circulating system, and means to maintain said pipes filled with a heating medium capable of extinguishing fires.

2. In a combined sprinkler and heating system, the combination with a plurality of sprinkler pipes, of a supply pipe connected to all of said pipes, a return also connected to all of said pipes, whereby said sprinkler pipes form part of a complete circulating system, and means to cause a heating medium capable of extinguishing fires to circulate through said pipes.

3. In a combined sprinkler and heating system, the combination with a plurality of sprinkler pipes, of a plurality of sprinkler heads mounted on each pipe, a supply pipe connected to all of said pipes, a return also connected to said pipes, means to maintain

said pipes filled with a heating medium capable of extinguishing fires, and means to close communication between said pipes and the return.

4. In a combined sprinkler and heating system, the combination with a plurality of sprinkler pipes, of a plurality of sprinkler heads mounted on each pipe, a supply pipe connected to said sprinkler pipes, a return also connected to said sprinkler pipes, means to heat and circulate a heating medium through said pipes, and means to stop the circulation of the heating medium without shutting off communication between said pipes and the supply. 70

5. In a combined heating and sprinkler system, a supply pipe, a return, a plurality of combined heating and sprinkler pipes connecting with both said supply and with said return, a plurality of sprinkler heads 75 mounted on each of said combined heating and sprinkler pipes, and independent means to close the communication between each of said pipes and the return whereby any one of the pipes may be cut out of the system as a heating pipe while remaining in the system as a sprinkler pipe. 80

6. In a combined heating and sprinkler system, a combined heating and sprinkler pipe connected with and forming part of a circulating system, sprinkler heads mounted 90 on said pipe, and means whereby the heating function of said pipe may be eliminated without affecting the sprinkling function thereof. 95

7. An automatic fire-extinguishing apparatus comprising a system of sprinkler pipes provided with heads, connections between their opposite ends forming a circulating system, connections between said system and a source of supply of water, and a heater included in said system. 100

8. In an automatic fire extinguishing system, an arrangement whereby water within such system may be constantly circulated and warmed and so protected from freezing, which consists of a combination of a heater, a conduit pipe connecting said heater with a manifold which unites the inlet ends of a series of distributing pipes having automatic distributing devices, a manifold uniting the extreme or outlet ends of said distributing pipes with each other and with a conduit leading to and connecting with said heater, the whole constituting a closed circuit including the automatic fire extinguishing system and the heater, substantially as described. 110

9. In an automatic stationary fire extinguishing system, the combination with distributing pipes provided with automatic distributing and discharge devices, of a water heater, a supply conduit connecting the said heater with a manifold uniting the inlets of the said distributing pipes, a return con- 115 120 125 130

duit connecting the said heater with a manifold uniting the outlet or dead ends of the said distributing pipes whereby a system is provided through which water may be circulated warm and so kept from freezing, substantially as described.

10. In an automatic stationary fire extinguishing system, the combination with water distributing pipes having automatic distributing devices, of a manifold uniting the inlet ends of such pipes, a water heater, a supply conduit connecting said heater with said manifold, a manifold uniting the extreme or outlet ends of the said distributing pipes with each other and with a return conduit connecting this manifold with the heater whereby water inclosed within the system may be circulated and warmed and so prevented from freezing, substantially as described.

11. The combination, with a sprinkler system, including supply and branch pipes, the latter provided with sprinkler heads, of a hot water heater having its outlet connected with the supply pipe, and a connection between the heater inlet and the outer ends of the branch pipes, whereby hot water can be circulated through the sprinkler system when in normal condition.

30 12. The combination, with a sprinkler system arranged for the continuous circulation of water therethrough under normal conditions, of means for heating and circulating water through the sprinkler system.

35 13. A sprinkler system, including supply pipes and sprinkler branches connected therewith, in continuous communication with a source of water supply, and means to permit circulation of water through the system, combined with means to heat and effect the circulation of the water through the sprinkler system.

40 14. The combination with a sprinkler system having branches provided with sprinkler heads, and water supplying pipes for said branches, of means to circulate water through the said supplying pipes.

45 15. A sprinkler system including branches provided with sprinkler heads, and water distributing and return pipes connected with the branches to permit circulation of water therethrough, and means to circulate water through the sprinkler system.

50 16. A sprinkler system including branches provided with sprinkler heads, and water distributing and return pipes connected with the branches to permit circulation of water therethrough, combined with a circulating pump having its inlet and outlet connected, respectively, with the return and distributing pipes, and means to heat the water in circulation.

55 17. A sprinkler system, a water supply in continuous communication therewith,

means to heat and circulate water through the sprinkler system, and a return connection between said system and the heating and circulating means.

18. The combination with water supply and return pipes, and a series of branches connected therewith and provided with sprinkler heads, to form a circulating system, of means to effect the circulation of water through such system.

19. The combination with water supply and return pipes, and a series of branches connected therewith and provided with sprinkler heads, to form a circulating system, of means to effect the circulation of water through such system, and means to heat the water as it passes to the circulating system.

20. The combination, with a sprinkler system including branches provided with sprinkler heads, and supply pipes for said branches, of means to effect the circulation of water through the supply pipes, and means to insulate the sprinkler heads from the heat of the circulating water.

21. The combination, with a sprinkler system arranged to form a closed circulating loop, and a water supply in continuous communication therewith, of means to effect the circulation of water through such circulating loop.

22. The combination, with a sprinkler system arranged to form a closed circulating loop, and a water supply in continuous communication therewith, of means to effect the circulation of water through such circulating loop, and means to raise the temperature of the water in circulation.

23. A circulation system of piping provided with sprinkler heads individually and automatically operative upon a predetermined rise in temperature, a source of water supply in constant communication with such system, and means separate from such source of supply to maintain in circulation the water in the piping system.

105 24. The combination, with a sprinkler system, including branches provided with sprinkler heads, and means to circulate hot water through the system, of connections between the branches and the sprinkler heads to form heat insulating bodies of dead air adjacent the sprinkler heads.

110 25. The combination, with a sprinkler system arranged to form a circulating loop for the water, of means to heat and circulate water through the system, and means to provide bodies of dead air adjacent the sprinkler heads and thereby insulate the latter from the heat of the water.

115 26. The combination with a plurality of branches provided with sprinkler heads, distributing and return pipes connected with the branches, means to effect the circulation

- of water through said pipes and branches, and means interposed between the distributing pipes and the branches to prevent short-circuiting of the water.
- 5 27. In a sprinkler system, a series of sprinkler branches distributing and return pipes connected therewith, means to heat and circulate water through the system, a source of water supply in constant communication with the system, and means to effect a substantially uniform distribution of water from the distributing pipes to the branches and thereby prevent short-circuiting.
- 10 28. The combination with a circulating system of sprinkler pipes provided with heads, of a heater included therein, connections between said system and a source of supply of water, a by-pass connection around the heater, and a valve controlling said by-pass connection.
- 15 29. In a sprinkler system, pipes arranged to form a circulation loop, means to circulate water therein, sprinkler pipes included in the circulation loop, sprinkler heads there-
- in, and a connection in the loop to a main supply of water.
30. In a circulating system, pipes and a water receptacle, arranged to form a circulation loop, means to circulate water therein, sprinkler pipes included in the circulation loop, sprinkler heads therein, and a connection in the loop to a main supply of water.
- 35 31. In a sprinkler system, pipes arranged to form a circulation loop, a circulating pump in said loop, sprinkler pipes included in the circulation loop, sprinkler heads therein, and a connection to a main supply of water entering the loop between the sprinkler pipes and the intake side of the circulating pump.
- 40 In testimony whereof, we have signed our names to this specification, in the presence of two subscribing witnesses.
